[57] CLAIM

The ornamental design for a front panel for a fireplace, substantially as shown and described.

DESCRIPTION

FIG. 1 is a perspective view of a front panel for a fireplace, showing our new design;

FIG. 2 is a front elevational view thereof;

FIG. 3 is a top plan view thereof;

FIG. 4 is a rear elevational view thereof;

FIG. 5 is a bottom plan view thereof;

FIG. 6 is a left side elevational view thereof; and

FIG. 7 is a right side elevational view thereof.

The broken line disclosure of a firebox in FIG. 1 is for illustrative purposes only and forms no part of the claimed design.
